Des. 230,248
Patented Feb. 5, 1974

230,248

TUBE BENDER

Laurice D. Ely, 2862 Stromboli Road,
Costa Mesa, Calif. 92626

Filed July 6, 1972, Ser. No. 269,470

Term of patent 14 years

Int. Cl. D8—05

U.S. Cl. D8—32

FIG. 1 is a perspective view of a tube bender showing my new design;

FIG. 2 is a front elevation view;
FIG. 3 is a back elevation view;
FIG. 4 is a side elevation view;
FIG. 5 is a top plan view;
FIG. 6 is a bottom plan view; and
FIG. 7 is a side elevation view.

I claim:

The ornamental design for a tube bender, as shown.
